SIDNEY J. FINN, OF BEVERLY, MASSACHUSETTS, ASSIGNOR TO UNITED SHOE MACHINERY CORPORATION, OF PATERSON, NEW JERSEY, A CORPORATION OF NEW JERSEY

FOXING APPLYING MACHINE

Application filed August 30, 1927. Serial No. 216,399.

This invention relates to machines for use in the manufacture of boots and shoes and is herein illustrated as embodied in a machine for applying a foxing to the lower margin or foxing area of a rubber-soled shoe.

In the manufacture of rubber-soled footwear having fabric uppers such as a tennis shoe or an arctic in which the sole is vulcanized to the upper, it is customary, after the shoe has been lasted but before the unvulcanized sole has been attached, to lay a narrow strip of unvulcanized rubber, known as a foxing, along the lower margin of the shoe, the lower part of the foxing being bent over upon the bottom of the shoe. After the foxing has been thus applied and the usual filler placed upon the bottom of the shoe, the unvulcanized rubber sole is laid on the bottom of the shoe and the rubber vulcanized. The foxing not only gives a neat appearance to the shoe but ensures a tight joint between the upper of the shoe and the sole.

Hitherto machines for performing operations upon the foxing area of a shoe, for example, machines for applying foxing, have required that the shoe be held by the operator and moved in a path to present the foxing area progressively to the operating mechanism. Such machines are not much faster than hand work and necessitate considerable skill on the part of the operator.

The general object of the present invention is to provide an automatic machine for operating upon the foxing area which shall be rapid and accurate and shall do away with the necessity for a skilled operator.

According to one feature of the present invention the shoe is mounted in a holder, and means are provided for producing relative movement between the shoe holder and a member for operating upon the shoe to cause a strip of foxing to be laid along the foxing area of the shoe. In the illustrated machine the shoe is held substantially upright and rotated about a vertical axis while a foxing applying member in the form of a roll is held yieldingly against the foxing area.

Due to the longitudinal curvature of the bottom of the shoe, the foxing area at the

heel end of the shoe is at a different level from that at the toe end. According to another feature of the invention, there is provided means for causing relative movement between the shoe and the operating member 55 heightwise of the shoe at the proper times during the applying of the foxing to compensate for this difference in level. In the illustrated machine, such heightwise movement is produced by causing the shoe to be 60 rocked forward and back at the proper times.

In order that foxing may be applied properly to shoes of different sizes, it is desirable that each shoe, whatever its size, be held in a certain predetermined relation to the axis about which it rotates. According, therefore, to another feature of the invention, means are provided for properly positioning each shoe prior to clamping it in place. In the illustrated machine, in which the upright shoe rotates about a vertical axis, means are provided for engaging the heel and toe ends of the shoe to move the shoe into a position in which the axis of rotation passes substantially through the middle of the shoe; and, after the shoe has been so positioned, it is clamped in the shoe holder.

After the foxing has been applied to the shoe it is desirable to press it firmly into place and to bend its lower portion to some extent over the bottom of the shoe. According to another feature of the invention a presser is provided for this purpose, the illustrated presser being an inflated rubber roll, 85 the yielding wall of which accommodates itself to the shape of the part of the shoe with which, at any given time, it is in engagement.

The upper edge of the foxing in the finished shoe should present a smooth line and not a wavy one. In order to ensure that the line shall be a smooth one, irrespective of any unevenness in width which may be present in the foxing, there is provided, according to another feature of the invention, mechanism 90 for trimming off the upper edge of the foxing before the foxing is applied to the shoe. In the illustrated construction this means comprises a disk cutter mounted on the top of the applying roll, and a smaller disk cutter 95

which cooperates with the first-named cutter and is driven from the applying roll.

These and other features of the invention including certain details of construction and combinations of parts will be described as embodied in an illustrative machine and pointed out in the accompanying claims.

Referring now to the accompanying drawings,

10 Fig. 1 is a front elevation of a machine in which the present invention is embodied, a shoe being shown held in position to be rotated, certain parts of the foxing applying mechanism, the greater part of which is 15 behind the shoe, as viewed in this figure, having been omitted so as not to confuse the showing of the shoe-holding means.

Fig. 2 is a perspective taken from the rear of the machine showing more particularly 20 the foxing applying mechanism.

Fig. 3 is a plan view of the mechanism by which the foxing applying member is carried,

25 Fig. 4 is a section of part of the machine on the line IV—IV of Fig. 1, the outline of the shoe being indicated by a dot-and-dash line,

30 Figs. 5 and 6 are similar to Fig. 3 but showing the mechanism in different positions. In these three figures the indenting wheel and part of the trimming mechanism have been omitted,

35 Fig. 7 is a section on the line VII—VII of Fig. 1 showing details of the driving mechanism,

Fig. 8 is a detail partly in section and partly in elevation showing more particularly the extensible link,

40 Fig. 9 is a detail in perspective of the cam which causes the shoe to be rocked.

Fig. 10 is a detail in section showing the laying of the foxing at a point in the shank portion of the shoe,

45 Fig. 11 is a detail, principally in section, showing the pressing of the foxing into place at a point in the shank portion of the shoe,

Fig. 12 is a plan showing more particularly the mounting of the indenting wheel, and the trimming mechanism, and

50 Fig. 13 is a detail in elevation of the treadle 83 and certain connected parts.

Before proceeding to a detailed description of the machine, a short description of its general mode of operation will be given. Referring first to Fig. 1, the shoe 100 on its last 200 is supported in a holder the upper and lower parts of which are carried respectively by aligned vertical shafts 21, 22; and, in the operation of the machine, these shafts are 25 rotated to impart a little more than a complete rotation to the lasted shoe. During this rotation a foxing applying member 23 (Fig. 2), in the form of a roll, applies a strip of foxing 300 along the lower margin of the shoe, which constitutes what may be termed

the "foxing area", the application being made through a belt 24 which runs over the roll and carries the foxing. Due to the longitudinal curvature of the bottom of the shoe, the foxing area at the heel end of the shoe is at a different level from that at the toe end. In order, therefore, to cause the foxing to be applied properly, it is necessary to produce at the proper times relative movement between the shoe and the applying member heightwise of the shoe. In the illustrated machine, the applying member remains always at the same level and the shoe is rocked or tilted. Foxing is applied to the rear part of the shoe,—that is, from the heel end to approximately the ball line—while the shoe is in the position shown in Fig. 1; and, when the forepart is reached, the shoe is rocked or tilted forward into the position shown in Fig. 2 and remains in that position while foxing is applied around the forepart.

80 The mechanism for holding and rotating the shoe comprises, as has been explained, the aligned shafts 21 and 22. The shaft 22 is mounted in vertical bearings in the frame of the machine and has fast to its upper end a hub 25 rigid with which is a bar 26 (Figs. 1 and 4). At one end of the bar is a support 27 for the rear part of the shoe, said support being connected with the bar by a pin 32 which extends into an upwardly extending slot in the support. The bar 26 passes through an elongated vertical slot in the support 27 so that the support may be pushed up at any time to rock the shoe. At the other end of the bar 26 is a support 28 for the forepart of the shoe, said support being slidably mounted on the bar by screws 29 which pass through downwardly extending flanges on the support 28 and through an elongated horizontal slot in the bar. A spring 30, located in the slot in the bar, urges the forepart support 28 at all times to the right, as viewed in Fig. 1. As shown in that figure the support 28 is being held in place by the forepart of the shoe which is clamped to it. If the shoe were removed, the support 28 would move to the right until arrested by contact of one of the screws 29 with the end of the slot in the bar 26. In Fig. 4 is shown 90 a plan view of the bar 26 and the supports 27 and 28. It should be noted that the forepart support 28 has two upstanding corrugated or toothed ridges 31 upon which the locality in the ball line of the shoe rests.

100 In Fig. 1, the shoe is shown held firmly between the aligned shafts 21 and 22 and with the middle point of the shoe lying substantially in the axis of said shafts. In order to position the shoe in this manner before 110 it is clamped to the supports 27 and 28, and while it is being steadied on the supports by the operator, two pushers 33, 34 are mounted for equal movement in opposite directions so that they are always equally distant from 115 120 125 130

the common axis of the shafts 21, 22. To this end the pushers are attached respectively to slides 35, 36 mounted on horizontal rods 37 and normally held apart by springs 39. Chains 40, 41, attached at their upper ends to the slides 35, 36, pass over suitable pulleys, and are connected at their lower ends to the upper end of a spring 42, the lower end of which is connected about midway between the ends of a treadle rod 43 pivoted at 44 and having a treadle 45. The operation of this shoe centering mechanism is as follows: Assuming that that part of the shoe holder (not yet described) which is associated with the shaft 21 is in raised position, the operator places the shoe upon the supports 27, 28, and depresses the treadle 45. The pushers 33, 34 thereby engage the toe and the heel of the shoe and center it with respect to the common axis of the shafts 21, 22; and during this centering movement an auxiliary pusher 47, associated with the toe pusher 33, engages the forepart support 28 and pushes it back against the force of the spring 30 so that it will be well out of the path of the foxing applying mechanism. When the shoe has thus been centered, the upper part of the shoe holder is brought down into the position shown in Fig. 1 to hold the shoe firmly in place.

The upper part of the shoe holder is in effect a clamp or jack having a small contact member 48 (Fig. 2) adapted to engage the toe portion of the upper of the shoe and a narrow plate 49 adapted to engage the top of the last. The toe member 48 is fast to a stem 51 which is threaded into a downwardly projecting cylindrical portion of a block 52, said block being slidable on a bar 53 and held in adjusted position by a set screw 54. When the shoe is rocked forward from the position shown in Fig. 1 to that shown in Fig. 2, it also rocks slightly sidewise, due to the transverse curvature of the bottom of the shoe. In order to permit this sidewise rocking, the last engaging plate 49 is supported at its forward end on the head of a screw 55 which is threaded into the forward extension of a block 57, said block, like the block 52, being slidable on the bar 53 and held in adjusted position by a set screw 59. The hole in the forward end of the last engaging plate 49 is larger than the stem of the screw 55 so that the forward end of the plate is merely hung upon the head of the screw. The rear end of the plate 49 is reversely bent as shown and extends over a shelf formed on the block 57, being prevented from swinging sidewise off the shelf by two stop pins one of which is shown at 60. The plate 49 has downwardly extending ears, one of which is shown at 61, to engage the sides at the top of the last. With this construction the slight sidewise rocking of the shoe, which has been referred

65 to above, is permitted since the plate 49 can

move somewhat with respect to the block 57. In order to facilitate such movement, a ball is interposed between the two. This ball is not shown, but is contained in the coiled portion 62 of a wire, the forward end of which encircles the screw 55 and the rear end of which extends through a hole in the bent-up portion of the plate 49.

When the shoe is rocked forward and back the bar 53 rocks with it; and to permit the bar so to rock, while the shoe is still held firmly clamped, the bar 53 has an upstanding lug (Fig. 1) fastened by a pivot screw 63 to a downwardly projecting lug on a slide 64 having rolls 65 which run on the ledges of an undercut guideway in an upwardly inclined guide member 66. A spring 67, located in the guideway tends to hold the slide 64 in the position shown in Fig. 1 against a stop, not shown.

The guide member 66 has projecting upwardly from it a boss in a socket in which the lower end of the shaft 21 is fastened by a pin 69. The shaft 21 is rotatably and slidably mounted in a vertical bearing formed in an overhanging arm 70 of the frame of the machine and is at all times urged upwardly by a coiled spring 71 which rests at its lower end upon the overhanging arm 70 and at its upper end engages the under side of a washer 72 which is loose on the shaft 21. Above the washer and separated from it by a ball thrust bearing (not shown) is a sprocket which is fast to the shaft 21; and around this sprocket, as well as around a sprocket fast to the upper end of a shaft 73, runs a chain 74, through which, as will presently appear, the shaft 21 is rotated from the shaft 22. Located above the sprocket on the shaft 21 is a second ball thrust bearing (not shown) and a second washer 75 the top of which is above the top of the shaft. Resting upon this washer is a cap-piece 76 having a cylindrical stem which is loosely received in a cylindrical socket in the top of the shaft. Fastened to the cap piece by a screw 77 is the upper end of a cord 78 which runs over guide pulleys 79, 80 and is attached at its lower end to the upper end of a spring 81, the lower end of which is attached to a treadle 83. The spring 81 is stronger than the coiled spring 71, which encircles the shaft 21; and consequently, when the treadle 83 is depressed, as it is shown in Fig. 1, the shaft 21 is moved down to cause the shoe to be held firmly against the toe and heel supports 27, 28. The treadle 83 is held depressed by a lug 163 during the rotation of the shoe and the laying of the foxing. After the laying operation has been finished, the treadle 83 is swung out from beneath the lug 163, whereupon the coiled spring 71 raises the shaft 21, and with it the upper shoe clamping members so that the shoe may be removed from the machine.

It has been stated above that the shoe, dur-

ing its rotation, is rocked or tilted from the position shown in Fig. 1 to that shown in Fig. 2 and back again. To this end (Figs. 2, 4 and 9) the hub 25 at the upper end of the vertical shaft 22 has an extension, in a horizontal bearing in which is rotatably mounted a short shaft 85 (Fig. 9) having integral with its outer end a crank arm 87 in which is fastened by a pin 89 a short spindle 90. Upon 10 this spindle are two rolls 91 and 92. The roll 91 runs, during a part of the revolution of the shoe, on a cam track shown in detail in Fig. 9. The roll 92, which is of slightly greater diameter than the roll 91, engages the 15 under side of the heel support 27, when the roll 91 rides up on the cam, and thereby rocks the shoe forward from the position shown in Fig. 1 to that shown in Fig. 2; and, when the roll 91 rides down and off the cam, the shoe is 20 permitted to rock back into the position shown in Fig. 1, under the influence of the spring 67 which is compressed when the shoe is rocked forward.

Before proceeding to a description of the 25 construction of the cam with which the roll 91 cooperates, it should be explained that the change in level between the rear portion of the foxing area on the shoe and the forward portion is gradual on the outer side of the 30 shoe and comparatively abrupt on the inner side of the shoe. In the illustrated machine the laying of the foxing begins at a point in the locality of the heel breast line on the far side of the shoe as viewed in Fig. 1 and takes 35 place progressively first around the heel end of the shoe, then along the side exposed to view in Fig. 1 and thence around the toe back to the point of beginning. At the start, the shoe is always held in the position shown in 40 Fig. 1. If the shoe is a right shoe, as shown in the figure, the foxing applying member will encounter first the gradual change in level of the foxing area on the outer side of the shoe and afterward the more abrupt 45 change on the inner side of the shoe. If, however, the shoe is a left shoe, the foxing applying member will encounter the more abrupt change in level first and the gradual change last. It is thus necessary to provide 50 two cams—or what amounts to two cams—to cooperate with the roll 91, one for right shoes in which the gradual rise comes first and the abrupt descent last, and the other for left shoes in which the abrupt rise comes first 55 and the gradual descent last. To this end the cam (Fig. 9) is made in two parts 93 and 94, the part 93 being fastened by screws 95 to the frame of the machine, and the part 94 being slidably mounted upon the part 93 60 by means of screws 96, which pass through slots 97 in the part 94 and are threaded into the part 93. The high portions of the parts are substantially flat and at the same level. The part 93 has comparatively abrupt inclines at both ends. The part 94 has com-

paratively gradual inclines at both ends. With the parts in the positions shown in Fig. 9 in which the part 94 occupies its right-hand position, the roll 91 will first run up the gradual incline on the part 94 and finally run down the more abrupt incline on the part 93, the parts being in position for a right shoe. If now a left shoe were to be operated upon the part 94 would be shifted to its left-hand position so that the roll 91 would first run up the abrupt incline on the part 93 and finally run down the gradual incline on the part 94. In order to facilitate adjustment of the part 94 there is mounted on it a spring-pressed locking pin 98 the end of which is adapted to be held in one or the other of two holes formed in the part 93. One of these holes is indicated at 99 in Fig. 9; the other is occupied by the pin.

The shaft 21 (Fig. 1) is driven from the shaft 22 through the chain 74, the upright shaft 73 and a second chain 101 which runs over a sprocket on the lower end of the shaft 73 and over another sprocket on the lower end of the shaft 22. The shaft 22 (Fig. 7) is driven from an upright shaft 102 by a chain 103 which passes around a sprocket 104 on the shaft 22, over a tightener pulley 105 and around a sprocket 106 on the shaft 102. The tightener pulley 105 is carried at the lower end of a lever 107 which is pivoted to the frame of the machine and may be moved to vary the position of the pulley 105 by turning a thumb-nut 108, said thumb-nut resting against the frame of the machine and being threaded upon one end of a pull-rod 109, the other end of which engages the upper end of the lever 107. The shaft 102, which has bearings at the top and bottom in the frame of the machine, is normally at rest, but may be caused to revolve by being clutched to a worm gear 110 which is driven continuously by a worm 111, the worm being fast to one end of a horizontal shaft 113 to the other end of which a pulley 114 is fast, said pulley being driven continuously from any suitable source of power, as for example the motor shown in Fig. 1. The gear 110 rotates on a downwardly extending sleeve which is rigid with the sprocket 106; and may be clutched to the shaft 102 by moving upwardly a clutch member 115 which is slidably keyed to the shaft. This clutch member has the usual groove to receive rollers, one of which is shown at 116 (Fig. 7) mounted in the arms of a forked lever 117 pivoted near its middle at 118 to the frame of the machine and at its outer end to the upper end of a treadle rod 119 which may be pulled down at any time by depressing a treadle 120 to which the lower end of the rod is connected.

The operation of the machine as thus far described is briefly as follows: Assuming that the treadle 83 is released and that consequently the shaft 21 and the upper clamp-

ing member carried by it are in raised position, a shoe is placed upon the supports 27, 28 and the treadle 45 depressed to cause the pushers 33, 34 to approach each other and thereby center the shoe with respect to the axis of the alined shafts 21, 22. The treadle 83 is then depressed and locked in depressed position; and the treadle 45 is released. Depression of the treadle 83, through the cord 78, pulls down the shaft 21 and the shoe clamping mechanism carried by it into the position shown in Fig. 1 in which the shoe is firmly held against the supports 27 and 28 by the member 48 which engages the toe portion of the shoe and the plate 49 which engages the top of the last. The treadle 120 is then depressed to impart rotation to the shafts 21 and 22 and is released when the shoe has completed slightly more than one revolution so that the ends of the applied foxing will overlap. The applying of the foxing starts, as has been explained, at about the heel breast line on that side of the shoe which is hidden from view in Fig. 1. During the rotation of the shoe and the applying of the foxing, the heel support 27 remains as in Fig. 1 until the foxing has been applied around the heel end of the shoe and well toward the ball line on that side of the shoe which is exposed to view in Fig. 1. At this stage of the application of the foxing, the roll 91 runs up and over the stationary cam 94, 93. The rise of the cam causes support 27 to be raised and the shoe to be rocked into the position shown in Fig. 2. The flat, high part of the cam holds the shoe in this position while the foxing is being applied around the forepart of the shoe; and then the descending part of the cam permits the shoe to be rocked back into the position shown in Fig. 1 and held there while the foxing is applied from the locality of the ball line to the point of beginning. It should be particularly noted that the shoe is held firmly in all positions to which it is tilted, the slide 64 moving up in the inclined guide 66 (Fig. 1), and the plate 49, which engages the top of the last, rocking slightly from side to side.

Referring now more particularly to Fig. 2, the mechanism for guiding the foxing to and pressing it against the foxing area of the rotating shoe will be described. As has been stated, the foxing applying member is the roll 23 around which passes the belt 24, a strip 53 of foxing 300 of the proper length being laid upon the belt and conducted to the shoe. The applying roll 23 is rotatable upon a small upright spindle mounted at the outer end of the arm 121, the inner end of which has a hub rotatably mounted upon an upright spindle 122, said spindle being fastened by a set screw 123 in a socket formed in an upwardly extending cylindrical boss on an arm 125 (see also Fig. 8). A torsion spring 126, fastened at its upper end to the hub of

the arm 121 and at its lower end to the boss urges the arm 121 at all times to swing toward the shoe. Fast to the arm 121 is one end of a twisted bar 127, from the other end of which is suspended by an upright bar 128 the horizontal spindle, upon which a roll or pulley 129 is rotatable. The belt 24, which has been referred to above, passes around this roll and around the applying roll 23; and this belt is driven by contact with the moving shoe.

As the foxing is laid progressively along the foxing area of the shoe, it is desirable that it should be pressed into firm contact with the shoe. To this end a presser 130, in the form of an inflated rubber roll, traverses the foxing area closely behind the applying roll 23. The presser roll is carried at the outer end of an arm 131 having a hub which, like that of the arm 121, is rotatable upon the upright spindle 122 and is urged at all times to swing toward the shoe by a torsion spring 132, fastened at one end to the hub of the arm 131 and at the other to a sleeve 133 which is fast to the stationary spindle 122. A brace 134, rigid with the spindle-supporting arm 125, has a cylindrical boss at its upper end through which the spindle 122 passes, a set screw 135 being threaded through the boss into contact with the spindle.

Located adjacent to the top of the applying roll 23 in position to trim the upper edge of the foxing before the foxing is applied to the shoe, is a trimming mechanism consisting of two cooperating disk cutters 169, 170; and also located adjacent to the top of the roll in position to act upon the foxing after it has been applied to the shoe is an indenting or so-called "stitching" wheel 164. Both the wheel and the mechanism are mounted upon the arm 121 and will be described later in detail. Due to the presence of the wheel and the mechanism, it is desirable that a substantially fixed relation be maintained between the spindle or carrier 122 and the roll 23, on the one hand, and, on the other hand, the locality on the rotating shoe at which the foxing is being applied, so that the applying roll will always occupy a position, such as that shown best in Fig. 2, in which the trimming mechanism 169, 170 is out of contact with the shoe, and the indenting wheel 164 operates upon the foxing just after the foxing has been applied. The objectionable result which would ensue upon changing this relation will be clear if it is supposed that, with the parts otherwise in the positions shown in Fig. 2, the spindle 122 should be swung considerably to the left. In such case the indenting wheel 164 would be moved more or less out of contact with the shoe, depending upon the extent to which the position of the spindle was changed, and the trimming mechanism might be moved into contact with the shoe if the spindle 122 were moved far

enough. The desirable relation referred to above is in general that the spindle or carrier 122, in all its positions, should be well ahead of the applying roll 23, considered in the direction that the foxing is being applied, and that the angle included between a plane tangent to the shoe at the point of application of the foxing and a plane passed through the axis of the roll 23 and the axis of the spindle 122 should always be an acute angle of substantially uniform size. Referring to Fig. 3, the two planes are indicated respectively by the dash lines A and B, the angle between them, in the illustrated construction, being 15 of the order of about thirty degrees.

It is obvious that, if no provision were made to maintain this relation, it would be disturbed most when the applying roll was moving around (so to speak) the toe or the heel of the shoe. The illustrated mechanism for moving the spindle or carrier 122 is constructed and arranged to move the carrier in a manner to preserve the relation which has been described above and particularly to 25 accelerate the forward movement of the carrier when foxing is being applied around the heel and around the toe of the shoe. Figs. 5 and 6 illustrate this accelerated movement. In Fig. 5 the applying roll 23 is approaching the toe end of the shoe; in Fig. 6 it has passed the toe end. The extent of movement of the applying roll from the position shown in Fig. 5 to that shown in Fig. 6 is small; but it will be noted that in the 30 same interval the spindle 122 has moved a much greater distance. Referring now to Fig. 4, which shows substantially the position in which the application of the foxing begins, the spindle 122 moves in the path of 35 a very much elongated figure 8, the long axis of which is substantially perpendicular to the longitudinal axis of the shoe in the position occupied by the shoe in that figure, the movement of the spindle being accelerated 40 at the curves at the top and bottom of the figure 8 path for the purpose which has been described above.

Referring now more particularly to Fig. 2 with occasional reference to Figs. 3 to 6, the spindle 122, as has been explained, is carried at the outer end of an arm 125. This arm is pivoted at its inner end at 136 to an extension on a main arm 137. This main arm is pivoted at its outer end about a stud 138 carried by a crank arm 139 which is fast to the upper end of the shaft 102 from which, as has been explained, the shoe is rotated. The other end of the main arm 137 is formed with two spaced guides which run in horizontal guideways formed in a block 140, which is loosely carried near the upper end of the shaft 22 upon which the shoe is supported. The stud or pivot 138 is fastened to the outer end of the crank arm 139; and 55 also fast to this stud is a short arm 141 so that

the two arms 139 and 141 are in effect one piece. The arm 141 is connected with the upright spindle 122 by an extensible link construction. Rising from the arm 141 is a shouldered stud, the upper end 143 of which is of reduced diameter and threaded. A gear 145 has a hole to receive loosely the threaded, reduced portion 143 of the stud and is clamped to the shoulder of the stud by a nut 147 so that the gear is rigid with the arm 141. Rotatable on the stud and located between the gear 145 and the arm 141 is one end of the upper member 148 of a two-part extensible link, best shown in Fig. 8, said member 148 being slotted as shown in Fig. 2. Below the upper member 148 of the extensible link is the lower member 149, one end of which is rotatable upon the upstanding cylindrical boss of the arm 125. This lower member has a guide stud 150 (Fig. 2) which extends up into the slot in the member 148; and the two members are slidably held together by a screw 151 which passes through the slot and is threaded into the lower member 149. In order to extend the link at the proper times, a gear 152, which is rotatably mounted upon the upper member 148 of the extensible link and meshes with the gear 145, has a crank pin 153 on which is pivoted one end of a connecting rod 155, the other end of said rod being pivoted on the upper reduced end of a stud 154 carried by the lower member 149 of the extensible link. A screw 156 holds the end of the connecting rod 155 on the stud 154. When the shaft 102 is rotated in the direction indicated by the feathered arrows in Figs. 5 and 6, the gear 145, which is rigid with the arm 141 and the arm 139, moves in an orbital path about the axis of said shaft and causes the gear 152 to make one rotation in the direction indicated by the plain arrows, for each complete orbital revolution of the gear 145. At each rotation of the gear 152, the extensible link, made up of the parts 148, 149, is completely extended and completely contracted. The shaft 102 (Fig. 7), owing to the fact that the diameter of the sprocket 106 is one-half the diameter of the sprocket 104, makes two rotations for a single rotation of the shoe. The link is, therefore, extended twice for each rotation of the shoe; and these extensions are timed to take place respectively when the foxing is being applied around the heel end and around the toe end of the shoe. In order to steady the outer end of the arm 125, said outer end runs in a guideway 176 (Fig. 2) formed in a bar 177 which is fast to the frame of the machine.

It is desirable that the foxing applying and pressing members should be automatically withdrawn from the shoe when the shoe is released preparatory to removing a shoe from the machine and that said members should be automatically moved into operative

position when a new shoe is clamped in place in the machine. To this end a cord 157 (Fig. 4), fastened at its upper end to the twisted bar 127, which is fast to the arm 121 by which the foxing applying member is carried, leads over a pulley 158 and down to one end of a lever 159 (Figs. 1 and 13). This lever is pivoted near its middle at 160 to the frame of the machine; and at its outer end is connected by a link 161 with the treadle 83. A tension spring 162 connects the inner end of the lever 159 with the frame of the machine. In the position of parts shown in Figs. 1 and 13, the lever 83 is depressed and held down by a lug 163 beneath which it has been swung. The cord 157 is slack at this time, and the foxing applying and pressing members are being held against the shoe by their respective springs. When, at the completion of the operation upon the shoe, the treadle 83 is swung from beneath the lug 163 and permitted to be pulled up by the springs 81 and 162, the lever 160 will be rocked in a counterclockwise direction as viewed in Fig. 13, whereby the cord 157 will be pulled down and the carrier arm 121 (Figs. 2 and 4) of the foxing applying member swung away from the shoe. The arm 121 will engage the carrier arm 131 so that both the foxing applying member and the presser will be pulled away from the shoe. The operator now removes the shoe which has been operated upon, places a new shoe in the machine, depresses the treadle 83 once more and locks it in depressed position. The parts are then again in the positions shown in Figs. 1 and 13 with the cord 157 slack and the foxing applying and pressing members in operative positions.

It is desirable to press the upper edge of the foxing firmly into contact with the shoe by running an indenting wheel along said edge. In the illustrated machine, such a wheel 164 (Fig. 12), which has been referred to above, is rotatably mounted at the outer end of an arm 165 which is pivoted at 166 to the arm 121 by which the foxing applying roll is carried. A spring 167 holds the arm 165 against the shoe. As fast, therefore, as the foxing is applied to the shoe it is indented along its upper edge by the wheel 164. The extent to which the arm 165 can be swung toward the shoe about its pivot 166 by the spring 167 is limited by reason of a stop (not shown) on the arm 121 with which a part of the arm 165 contacts.

It is very desirable that the upper edge of the foxing in the finished shoe should present a smooth, unbroken line and not a wavy one. In order to ensure that any unevenness in the width of the foxing or any slight displacement of it on the belt 24 shall not result in a wavy edge at the top of the foxing in the finished shoe, means are provided for trimming the upper edge of the foxing.

To this end, two cooperating disk cutters

169, 170 (Fig. 12) which have been referred to above are provided. The cutter 170 is fast to the lower end of a small stem 171 which is rotatable in the end of an arm 172, said arm being integral with or fastened to the arm 121. The disk cutter 169 is clamped to the top of a sleeve 269 (Fig. 2) which is rotatable upon an upright spindle carried by the arm 121, the cutter 169 being held down in contact with the cutter 170 by a coiled spring 271 the upper end of which engages the under side of a washer, said washer being fastened to the top of the upright spindle by a screw 273. The sleeve 269 is driven from the applying roll 23 (Fig. 12) by means of a gear 173 fast to the lower end of the roll which meshes with a smaller gear 274 fast to the lower end of the sleeve. Thus, whenever the foxing applying roll is rotating, the cutters 169, 170 are also rotating and serve to trim the upper edge of the foxing. In order to guide the foxing properly to the trimming cutters 169, 170, an upright guide roller 174 for the carrier belt 24 is provided. In this connection, it should be noted that the belt 24 has extending along its lower edge a ledge 175 (Fig. 2) upon which the lower edge of the foxing rests when passing to and around the applying roll 23.

The complete operation of the machine is briefly as follows. Assuming that the treadle 83 (Fig. 1) is released, in which case the upper clamping member for the shoe will be in raised position and the cord 157 will be holding the foxing applying and pressing rolls in inoperative positions, a shoe is placed upon the supports 27, 28 and the treadle 45 depressed whereupon the pushers 33, 34 center the shoe with respect to the axis of the shaft 22 about which it is to rotate. The treadle 83 is then depressed and locked in depressed position, and the treadle 45 released. Depression of the treadle 83 moves the shaft 21, with its attached shoe clamping members down to clamp the shoe firmly in place, and at the same time allows the cord 157 to become slack so that the torsion springs 126, 132 (Fig. 2) may swing the foxing applying and pressing rolls into operative position. A strip of foxing of the proper length is placed upon the belt 24 and the treadle 120 depressed and held down until the shaft 102 has made two revolutions and a fraction, whereupon the shaft 22, which carries the shoe, makes slightly more than one revolution. The upper edge of the foxing is trimmed by the small disk cutters 169, 170 just before the foxing is applied to the shoe; and, just after it has been applied, it is indented by the wheel 164 and pressed firmly into place by the inflated rubber presser 130.

Although the invention has been set forth as embodied in a particular machine, it should be understood that the invention is

not limited in the scope of its application to the particular machine which has been shown and described.

Having thus described my invention, what I claim as new and desire to secure by Letters Patent of the United States is:—

- 5 1. A machine of the class described having, in combination, a base, a holder for a shoe, two members for operating successively upon the shoe, a common support for the members separate from the base, and means for producing relative movement between the shoe holder and the support to cause the foxing area to be traversed successively by said members.
- 10 2. A machine of the class described having, in combination, a holder for a shoe, a member for operating upon the shoe, and mechanism for producing relative movement between the member and the shoe holder to cause the foxing area of the shoe to be traversed by the member, said mechanism including a carrier for the member, and means for maintaining the carrier at all times in advance of the member considered in the direction in which the foxing area is being traversed.
- 15 3. A machine of the class described having, in combination, a holder for a shoe, a member for operating upon the shoe, and mechanism for producing relative movement between the member and the shoe holder to cause the foxing area of the shoe to be traversed by the member, said mechanism including a carrier for the member and means including an extensible link for maintaining the carrier at all times in advance of the member.
- 20 4. A machine of the class described having, in combination, a support for an article having an outline which includes a sharply convex portion, a member for operating upon the article, and mechanism for producing relative movement between the support and the member to cause the article to be traversed by the member, said mechanism including means for accelerating said relative movement during the traverse by the member of that portion of the article the outline of which is sharply convex.
- 25 5. A machine of the class described having, in combination, a holder for a shoe, means for supporting a foxing strip, and means for producing relative movement between the shoe holder and the foxing supporting means in a predetremined path to apply the foxing along the lower margin of the shoe.
- 30 6. A machine of the class described having, in combination, a holder for a shoe, a foxing applying member, and means for producing relative movement between the shoe holder and the applying member in a predetermined path to cause the lower margin of the shoe to be traversed by the applying member.
- 35 7. A machine of the class described having,

in combination, a holder for a shoe, a foxing applying member, and means for producing relative movement between the shoe holder and the applying member to cause the lower margin of the shoe to be traversed by the applying member, said means including means for causing relative movement between the applying member and the shoe holder heightwise of the shoe to provide for the difference in level between the toe portion and the heel portion of said lower margin.

8. A machine of the class described having, in combination, a holder for a shoe, a foxing applying member and means for producing relative movement between the shoe holder and the member to cause the lower margin of the shoe to be traversed by the applying member, said means including mechanism for holding the shoe in one angular position during the traverse of the toe portion of the margin and in another angular position during the traverse of the heel portion.

9. A machine of the class described having, in combination, a belt for supporting a foxing, a support for securely holding a shoe, and means for causing relative movement between the shoe support and the belt to transfer the foxing from the belt to the shoe.

10. A machine of the class described having, in combination, a holder for a shoe, means for moving the mounted shoe in a predetermined path, and means for progressively applying a foxing along the lower margin of the moving shoe.

11. A machine of the class described having, in combination, means for rotating a shoe about an axis extending heightwise of the shoe, a member for applying foxing to the lower margin of the shoe, and means for causing relative movement between the shoe and the member heightwise of the shoe during the rotation of the shoe to provide for the difference in level between the toe portion and the heel portion of said margin.

12. A machine of the class described having, in combination, a member for supporting a foxing, and means for moving a shoe in a predetermined path past said member to cause foxing to be applied along the lower margin at one end of the shoe and for tilting the shoe during its movement to cause foxing to be applied along the lower margin at the other end of the shoe.

13. A machine of the class described having, in combination, a support for a shoe, means for rotating the shoe about an axis extending heightwise of the shoe, a foxing applying member, means for holding the member against the shoe in the locality of the lower margin thereof, and means for tilting the shoe about an axis extending widthwise of the shoe during its rotation.

14. A machine of the class described having, in combination, a support for a shoe,

- means for rotating the shoe about an axis extending heightwise of the shoe, a foxing applying member, means for holding the member against the shoe in the locality of the lower margin thereof, and means for rocking the shoe forward and back during its rotation. 5 70
15. A machine of the class described having, in combination, means for rotating a shoe about an axis extending heightwise of the shoe, a foxing applying member mounted for movement in a plane at right angles to the axis, and means for moving a portion of the shoe heightwise during its rotation to cause the applying member to follow the contour of the lower edge of the shoe. 10 75
16. A machine of the class described having, in combination, a member for applying a foxing progressively to the lower margin of a shoe, and means for trimming the foxing during the applying operation. 20 80
17. A machine of the class described having, in combination, a member for applying a foxing progressively to the lower margin of a shoe, and means associated with the applying member for trimming the foxing during the applying operation. 25 85
18. A machine of the class described having, in combination, a support for a shoe, means for applying a foxing progressively to the lower margin of the shoe, and cooperating shear cutters for trimming the foxing during the applying operation. 30 90
19. A machine of the class described having, in combination, a support for a shoe, a roll for applying a foxing progressively to the lower margin of the shoe, and cooperating cutters driven by the roll for trimming the foxing during the applying operation. 35 95
20. A machine of the class described having, in combination, a support for a shoe, a foxing applying member, means for locating the shoe on its support, and means for producing relative movement between the shoe support and the foxing applying means to apply foxing along the lower margin of the shoe. 40 100
21. A machine of the class described having, in combination, a support for securely holding a shoe, a foxing indenting tool, and means for producing relative movement between the shoe and the tool to cause the lower margin of the shoe at a locality above the sole thereof to be traversed by the tool. 45 105
22. A machine of the class described having, in combination, a support for a shoe, an indenting tool, and means for producing relative movement between the shoe and the tool to cause the lower margin of the shoe to be traversed by the tool, said means including means for causing relative movement between the indenting tool and the shoe support heightwise of the shoe to provide for the difference in level between the toe portion and the heel portion of said lower margin. 50 110
23. A machine of the class described having, in combination, a support for securely holding a shoe, a foxing applying member, an indenting tool, and means for producing relative movement between the shoe support on the one hand and the applying member and the tool on the other hand to cause the lower margin of the shoe to be traversed by the member and the tool. 55 115
24. A machine of the class described having, in combination, a support for securely holding a shoe, a foxing applying member, a presser member, and means for producing relative movement between the shoe support and the two members to cause the foxing to be applied along the lower margin of the shoe and pressed into firm contact with the shoe. 60 120
25. A machine of the class described having, in combination, a support for securely holding a shoe, a foxing applying member, a presser member, and means for producing relative movement between the shoe support and the two members to cause the lower margin of the shoe to be traversed by the members. 65 125
26. A machine of the class described having, in combination, a support for securely holding a shoe, a foxing applying member, an indenting member, a presser member, and means for producing relative movement between the shoe support and the three members to cause the foxing to be applied along the lower margin of the shoe, indented and pressed into place. 70 130
27. A holder for a lasted shoe comprising two supporting members, one for the rear portion and the other for the forward portion of the bottom of a shoe, means for raising and lowering one of the members to rock the shoe on the other member, and clamping mechanism for pressing the shoe against the supporting members constructed and arranged to accommodate itself to any position to which the shoe is rocked. 75 135
28. A holder for a lasted shoe comprising two supporting members, one for the rear portion and the other for the forward portion of the bottom of a shoe, means for raising and lowering one of the members to rock the shoe on the other member, and clamping mechanism for pressing the shoe against the supporting members, said mechanism including members for engaging respectively the neck of the last and the forepart of the shoe, and a carrier for said last-named two members adapted to be rocked when the shoe is rocked. 80 140
29. A machine of the class described having, in combination, a support for a shoe, a foxing applying member, and mechanism for producing relative movement between the support and the member to cause the lower margin of the shoe to be traversed by the member, said mechanism including a carrier for the member, and means for maintaining

the carrier at all times in advance of the member considered in the direction in which the foxing is being applied to the shoe.

30. A machine of the class described having, in combination, a support for a shoe, a foxing applying member, and mechanism for producing relative movement between the support and the member to cause the lower margin of the shoe to be traversed by the member, said mechanism including a carrier for the member, and means including an extensible link for maintaining the carrier at all times in advance of the member considered in the direction in which the foxing is being applied to the shoe.

31. A machine of the class described having, in combination, a support for a shoe, means for rotating the support, a foxing applying member, a carrier for said member located in advance of said member considered in the direction in which the foxing is applied to the shoe, and mechanism for moving the carrier in a path to cause the applying member to follow substantially the edge of the rotating shoe, said mechanism including means for accelerating the movement of the carrier during the traverse by the applying member of the toe portion of the shoe.

32. A machine of the class described having, in combination, a support for a shoe, means for rotating the support, a foxing applying member, a carrier for said member located in advance of said member considered in the direction in which the foxing is laid on the shoe, and mechanism for moving the carrier in a path to cause the applying member to follow the lower edge of the rotating shoe, said mechanism including an extensible link with which the carrier is connected, and means for extending the link to accelerate the movement of the carrier during the traverse by the applying member of the toe portion of the shoe.

33. A machine of the class described having, in combination, a holder for a shoe, a member for operating upon the foxing area of the shoe, means for preliminarily engaging the shoe and adjusting it with respect to its holder so as to position it properly in the holder, and means for producing relative movement between the shoe holder and the member to cause the foxing area of the shoe to be traversed by the member.

34. A machine of the class described having, in combination, a member for operating upon the foxing area of a shoe, a holder for a shoe including elements between which the shoe may be clamped, means for locating the shoe in its holder, means for thereafter operating the clamping elements to fix the shoe in position, and means for producing relative movement between the shoe holder and the operating member to cause the foxing area of the shoe to be traversed by said member.

35. A machine of the class described having, in combination, a member for operating upon the foxing area of a shoe, a rotary holder for a shoe including elements between which the shoe may be clamped, means for engaging the shoe to center it with respect to the axis of rotation of its holder, means for thereafter clamping it in place, and means for producing relative movement between the shoe holder and the operating member to cause the foxing area of the shoe to be traversed by the member.

36. A machine of the class described having, in combination, a clamp for holding a shoe, a member for operating upon the foxing area of the shoe, and a single means, manipulation of which causes the clamp to close upon the shoe and the member to move into engagement with the shoe.

37. A machine of the class described having, in combination, a clamp for holding a shoe, a member for operating upon the foxing area of the shoe, and a single means, movement of which in one direction causes the clamp to close upon the shoe and the member to move into engagement with the shoe, and movement of which in another direction causes the clamp to release the shoe and the member to move away from the shoe.

38. A machine of the class described having, in combination, a flexible member for supporting a foxing, a support for securely holding a shoe, and means for causing relative movement between the shoe support and the flexible member to transfer the foxing from the member to the shoe.

39. A machine of the class described having, in combination, a carrier for a shoe, means for engaging a foxing, means for producing relative movement between the shoe carrier and the foxing engaging means in a predetermined path to apply the foxing to the shoe, and means for producing relative movement between the shoe carrier and the foxing engaging means heightwise of the shoe during said application to cause the foxing to follow the longitudinal curvature of the bottom of the shoe.

40. A machine of the class described having, in combination, foxing applying means, and means for moving the shoe bodily and angularly to present the foxing area thereof to the foxing applying means.

41. A machine of the class described having, in combination, supporting means upon which a single foxing of proper length may be placed, a holder for securely supporting a shoe, and means for transferring the foxing from the foxing supporting means to the shoe.

42. A machine of the class described having, in combination, a support for securely holding a shoe, a foxing applying member constructed and arranged to support a piece of foxing of proper length, a presser member, and means for producing relative move-

ment between the shoe support and the two members to cause the foxing to be moved progressively between the two members and the shoe and to be applied along the foxing area of the shoe.

43. A machine of the class described having, in combination, a support for a shoe, a foxing applying member, a presser member having an operative face adapted yieldingly to conform to the contour of the foxing area of the shoe, and means for producing relative movement between the shoe support and the two members to cause the lower margin of the shoe to be traversed by the members.

44. A machine of the class described having, in combination, a support for a shoe, a hollow presser member having a thin pliable wall constructed and arranged to be bent to accommodate itself to the variations in the contour of the lower margin of the shoe, and means for producing relative movement between the shoe support and the presser to cause said lower margin to be traversed by the presser.

45. A machine of the class described having, in combination, a support for a shoe, a foxing applying member, a presser member closely adjacent thereto and having a pliable face adapted to mould a foxing to the contour of the foxing area of the shoe, and means for producing relative movement between the support and the two members to cause said area to be traversed by the members.

46. A machine of the class described having, in combination, a holder for a shoe, a foxing applying member, a member by which said member is carried, said carrier member being movable toward and from the shoe, yielding means acting to urge the carrier member, and with it the foxing applying member, toward the shoe, and means for producing relative movement between the carrier member and the shoe to cause the foxing applying member to apply foxing progressively to the foxing area of the shoe.

47. A machine of the class described having, in combination, a holder for a shoe, a foxing applying member, a member by which said member is carried, said carrier member being angularly movable toward and from the shoe about an axis extending heightwise of the shoe, yielding means acting to urge the carrier member, and with it the foxing applying member, toward the shoe, and means for producing relative movement between the carrier member and the shoe to cause the foxing progressively to the foxing area of the shoe.

48. A machine of the class described having, in combination, a holder for a shoe, a foxing applying roll and a foxing pressing roll arranged side by side to operate upon the shoe at two points located adjacent to each other on the foxing area of the shoe, and means for producing relative movement

between the shoe and the two rolls to cause the foxing to be applied progressively to the shoe and progressively pressed against the shoe.

49. A machine of the class described having, in combination, a holder for a shoe, a member adapted to apply foxing to a shoe, a presser member arranged to follow the applying member, a carrier for the applying member, a carrier for the presser member, yielding means for urging the carriers toward the shoe, and means for producing relative movement between the carriers and the shoe holder to cause the foxing area of the shoe to be traversed by said members.

50. A machine of the class described having, in combination, a holder for a shoe, a member adapted to apply foxing to a shoe, a presser member arranged to follow the applying member, a carrier for the applying member pivoted about an axis which extends heightwise of the shoe, a carrier for the presser member also pivoted about an axis which extends heightwise of the shoe, yielding means for urging said members toward the shoe, and means for producing relative movement between the carriers and the shoe holder to cause the foxing area of the shoe to be traversed by said members.

51. A machine of the class described having, in combination, a holder for a shoe, a member for applying foxing to a shoe, a member located adjacent to the applying member for pressing the foxing against the shoe, yielding means for urging the members toward the shoe, means for producing relative movement between the shoe holder and the members to cause the foxing area to be traversed by the members, and means for withdrawing the members from the shoe.

52. A machine of the class described having, in combination, a holder for a shoe, a belt adapted to support foxing, means for producing relative movement between the belt and the shoe holder, and means responsive to said relative movement for causing the belt to move in a direction to deliver foxing to the shoe.

53. A machine of the class described having, in combination, a movable holder for a shoe, a belt adapted to support foxing, and means responsive to movement of the shoe when the holder is moved for causing the belt to deliver foxing to the shoe.

54. A machine of the class described having, in combination, a movable shoe holder, a belt adapted to support foxing, a carrier for the belt, yielding means for urging the carrier toward a shoe carried by the holder, and means responsive to movement of the shoe with the shoe holder for causing the belt to move in a direction to deliver foxing to the shoe.

55. A machine of the class described having, in combination, a shoe holder, a belt,

a carrier for the belt, yielding means for swinging the carrier toward the shoe, means for causing relative movement between the shoe holder and the carrier, and means operated by said relative movement for causing the belt to deliver foxing to the shoe.

56. A machine of the class described having, in combination, a holder for a shoe, a belt for supporting foxing to be applied to the shoe, means for urging a portion of the belt toward the shoe to cause the foxing to contact with the shoe, and means for producing relative movement between the belt and the shoe holder to cause the belt to deliver foxing to the shoe.

57. A machine of the class described having, in combination, a holder for a shoe, a belt for supporting foxing to be applied to the shoe, means for urging a portion of the belt toward the shoe to cause the foxing to contact with the shoe, and means for moving the shoe holder to cause the belt to deliver foxing to the shoe.

58. A machine of the class described having, in combination, a holder for a shoe, a belt for supporting foxing and delivering it to the shoe, rolls around which the belt runs, yielding means for causing one of the rolls, acting through the belt, to hold a portion of the foxing against the shoe, and means for producing relative movement between the belt and the shoe holder to rotate the roll in a direction to cause the belt to deliver foxing to the shoe and to cause the roll to apply foxing to the foxing area of the shoe.

59. A machine of the class described having, in combination, a holder for a shoe, a quarter-turn belt having a run adapted to support foxing, there being a raised portion along one edge of the belt to prevent the foxing from slipping from a portion of the supporting run of the belt which at any time may be inclined to the horizontal, and means for producing relative movement between the shoe holder and the belt to cause foxing to be applied to the shoe.

60. A machine of the class described having, in combination, a support for a shoe, an inflated presser roll adapted to accommodate itself to the variations in contour of the foxing area of the shoe, and means for producing relative movement between the shoe and the presser roll to cause the foxing area of the shoe to be traversed by the roll.

61. A machine of the class described having, in combination, a support for securely holding a shoe, a foxing-applying member, a presser member, and means for producing relative movement of rotation and translation between the shoe support and the two members to cause the foxing to be applied along the lower margin of the shoe and pressed into firm contact with the shoe.

62. A machine of the class described having, in combination, a support for securely

holding a shoe, two members for operating successively upon the same side of the shoe at the same time, and means independent of the shoe for producing relative movement of rotation and translation between the shoe support and the two members to cause the foxing area to be traversed successively by said members.

63. A machine of the class described having, in combination, means for securely holding a shoe, and means for supporting a foxing strip, said two means being relatively movable to apply the foxing along the lower margin of the shoe.

64. A machine of the class described having, in combination, a support for securely holding a shoe, two rollers for operating successively upon the foxing area on the same side of the shoe at the same time, means for producing the movement of rotation of the shoe support, and for moving the rollers bodily to cause the foxing area of the shoe to be traversed by the rollers.

In testimony whereof I have signed my name to this specification.

CERTIFICATE OF CORRECTION.

Patent No. 1,863,747.

June 21, 1932.

SIDNEY J. FINN.

It is hereby certified that error appears in the printed specification of the above numbered patent requiring correction as follows: Page 4, line 32, for "beings" read "begins"; and line 79, for "park" read "part"; page 6, line 9, for "aris" read axis"; and line 89, for "theraded" read "threaded"; page 11, line 57, claim 47, before "progressively" insert the words "applying member to apply foxing"; and that the said Letters Patent should be read with these corrections therein that the same may conform to the record of the case in the Patent Office.

Signed and sealed this 23rd day of May, A. D. 1933.

(Seal)

Acting Commissioner of Patents.
